 1 Claim. (Cl. 248—226)

ABSTRACT OF THE DISCLOSURE

A reflecting guide post holder detachably connecting the post to a crash barrier support, the holder including a multi-dimensional displaceable joint for permitting the guide post to be oriented to a desired position and to be immovably fixed in that position.

The present invention relates to light reflecting guide posts for traffic, having means for connection to crash barriers bordering traffic lanes.

From experience it is found that the supports of the guide posts and crash barrier rails associated with a roadway, which in most cases are driven into the ground, rarely assume a perpendicular position, so that a correct positional arrangement of the guide posts is rarely obtained. Thus, it is an object of the invention to provide a light reflecting guide post for traffic which is adapted to be detachably connected by means of a holder to a crash barrier so as to eliminate the adverse effects created by vertical misalignments of the crash barrier.

Hitherto for the purpose of connecting the guide posts to the crash barrier rail support, there has been provided on the lower end of the guide post, of substantially triangular cross-section and mostly made of wood, a metal plate. This plate, which projects downwardly of the post serves as a holder and has a slot extending in the longitudinal direction of the post and open in the direction of the free end of the plate. The plate is inserted between the crash barrier rail and its support and clamped in position by means of fixing screws engaging through holes in the barrier rail and its support and the slot in the plate.

According to the present invention, there is provided a light reflecting guide post for traffic adapted to be detachably connected by means of a holder to a crash barrier support, characterised by the feature that the holder has a multi-dimensional displaceable joint adapted to be positively fixed. The holder has a joint which is angularly displaceable in a multi-dimensional manner and which is adapted to be fixed positively, and as a fixing means for the holder, there is provided a suitable multiple clip to be connected to the support of a crash barrier rail, the limbs of which clip extend substantially axially parallel to the longitudinal extension of the guide post. The joint and the guide post are supported by the clip which in turn is supported by the barrier support.

Preferably the clip is arranged on an intermediate member so as to be pivoted and fixable in the substantially vertical plane and the intermediate member in turn is adapted to be pivoted and fixed in a vertical plane arranged at right angles to the latter plane on the guide post, or connected to the guide post or a plate, protruding therefrom, or the like.

Furthermore, an advantageous and inventive further development of the above described subject matter is characterised by the feature that between the links of the joint, means are provided for the positive connection, such as fan-shaped discs.

An alternative embodiment of the invention is also envisaged in which that joint is a fixable ball joint.

2

In the manner described a guide post is obtained in the form of a light reflecting traffic sign which is adapted to be connected to a crash barrier, preferably to its support, so that the angle of incidence and angle of reflection of the light beams striking the reflecting surfaces of the guide post can be regularly aligned relative to the roadway. Thus, a correctly aligned guide post as described in the invention is produced with simple means and at relatively low cost.

10 The invention will now be described further, by way of example, with reference to the accompanying drawings, in which:

FIG. 1 is an end view of the connecting means for a guide post according to the present invention;

15 FIG. 2 is a side view of FIG. 1;

FIG. 3 is a view taken along the line 1—1 of FIG. 1; FIG. 4 is a further embodiment of a guide post in front elevation;

FIG. 5 is a side view of FIG. 4;

20 FIG. 6 is a view taken along the line 2—2 of FIG. 4. In both illustrated embodiments of the invention, the guide post 1 may be clamped firmly in position to the barrier support by means of a multiple clip 2 adapted to be continuously displaceable longitudinally on the support

25 of a barrier rail. This clip serves for connection, for example, to L-shaped supports, as shown in the drawings, or to cylindrical supports, not shown, in which latter case may be formed as a pipe clip. The clip of FIGURES 1 to 3 is journaled in a pivotable manner and is positively fixable to a U-shaped intermediate member 3 by means of two bolts 5 and 6 arranged in spaced relationship to one another and engaging through an angled flange 4 of the clip 2 and the web of the intermediate member 3. One of the bolts passes through an arcuate slot 7 in the intermediate member 3, slot 7 serving to permit the clip 2 to be pivoted through a small angle about the horizontal longitudinal axis of bolt 6.

30 This intermediate member 3 is journaled, in the same manner as the clip 2 on the intermediate member 3, by means of two bolts 8 and two rivets 9 to a further U-shaped member 10 secured to the guide post 1. In order to permit guide post 1 to be properly angularly oriented the U-section 10 is provided with flanges having arcuate slots 11 formed to receive screws 8, the slot 11 permitting the guide post to be pivoted through a small angle about the horizontal longitudinal axis of bolt 9, which axis is perpendicular to the axis about which member 3 can pivot with respect to clip 2. Wood screws 12 serve to fix the U-shaped member 10 to the guide post 1.

35 In the alternative embodiment illustrated in FIGS. 4 to 6, wherein like reference numerals designate elements which are identical with those of FIGURES 1 to 3, the clip 2 is connected to an angled member 13 and the latter in turn is connected pivotally and fixably to the guide post 1. The references 14 and 15 designate the support and barrier rail, respectively.

40 As in the case of the embodiments of FIGURES 1 to 3, the provision of slots 7 and 11 in the embodiments of FIGURES 4 to 6 permit the guide post to be pivoted, within a certain range, into any desired angular position with respect to two mutually perpendicular horizontal axes coaxial with the axes of bolts 6 and 12, respectively.

45 It will be understood that the above description of the present invention is susceptible to various modifications, changes, and adaptations, and the same are intended to be comprehended within the meaning and range of equivalents of the appended claim.

What is claimed is:

50 1. In combination with a reflecting guide post for traffic:

(a) a holder detachably connecting said post to a crash

barrier support, said holder including a multi-dimensional displaceable joint for permitting said guide post to be oriented to a desired position and to be immovably fixed in that position; and

- (b) fixing means for said holder to be secured to the support of a crash barrier rail, said fixing means including a multiple clip having a clip yoke whose axis extends substantially axially parallel to the longitudinal extension of the support, said yoke supporting said joint and the latter, in turn, supporting the guide post, said clip being arranged so as to be pivotal in a first substantially vertical plane;
- (c) said holder being constituted by a plate and an intermediate member, said intermediate member being connected to said plate and the latter being

5

10

15

arranged in a second substantially vertical plane which is at right angles to said first substantially vertical plane, said plate being arranged to be pivoted and fixed to the guide post or projecting from the latter so as to be pivotal and fixable.
